UNITED STATES PATENT OFFICE

ALVIN C. RASMUSSEN, RAYMOND DORWARD, AND LYMAN CLAIRE GEROW, OF INDIANAPOLIS, INDIANA, ASSIGNEES TO INSLEY MANUFACTURING COMPANY, OF INDIANAPOLIS, INDIANA, A CORPORATION OF INDIANA

DITCHER

Application filed April 18, 1929. Serial No. 356,043.

The object of our invention is to provide an efficient excavating device of the type wherein an excavating bucket is carried at the lower end of a swinging bucket stick 5 which is pivotally and slidably associated with a vertically swinging boom by which it is carried, means being provided for raising and lowering the boom and for positively swinging the bucket stick in both directions 10 on the boom and for positively shifting the bucket stick longitudinally relative to its pivotal mounting.

The accompanying drawings illustrate our invention.

15 Fig. 1 is a side elevation of an embodiment of our invention;

Fig. 2 a plan;

Fig. 3 a side elevation of another embodiment, and

20 Fig. 4 a plan of the embodiment shown in Fig. 3.

In the drawings 10 indicates a boom stepped, at 12, upon a horizontal axis so that the boom may swing in vertical planes, the 25 step 12 being conveniently, and most generally, carried upon a turn table 13, supported by a suitable traction device (not shown) of common form, the completed mechanism embodying a well known mechanism by 30 means of which the turn table with its associated parts may be swung about a vertical axis.

Supported at or near the outer end of boom 10 is a pivot pin 15 upon which is pivoted 35 a yoke 16 in which is slidably mounted a bucket stick 17 to the lower end of which is secured a suitable excavating bucket 18. The association of parts 15, 16 and 17 is such that the stick 17 may swing about pin 15 40 and may slide lengthwise in yoke 16 and relative to pin 15.

Journaled upon pin 15, at each side of yoke 16 is a sheave 19.

Referring now to Figs. 1 and 2, 20, 20 are 45 two stiff links, capable of acting either as struts or ties, which, at their outer ends are pivotally connected at 21 to the bucket stick 17 beyond pin 15, and at their inner ends are pivotally connected at 22 to boom 10 between 50 step 12 and pin 15.

In the form shown in Figs. 3 and 4, instead of links 20, I provide links 20' which, at one end are pivotally connected at 22 to the boom, and at their other ends are pivotally connected at 23 with the upper end of 55 stick 17.

A bumper block 25 is secured to the upper side of the boom in position to be engaged by the upper end of the stick 17 when said stick 60 is in its extreme projected position.

In order to draw the bucket towards the base of the boom, I provide a pull line 30 which extends from a winding drum 31 to the lower end of the stick. The precise form of connection between this pull line and the lower end of the stick may be varied to a considerable extent, depending upon the desired force to be applied to the bucket to move the same towards the base of the boom and in the drawings I have illustrated this connection as a bail 32 attached to an ear 32' connecting the bucket and stick, and a sheave 33 over which the pull line is reeved, said line being also reeved over a sheave 34 journaled at 35 at an intermediate point in the length 70 of the boom.

Suitable well known means (not shown), will be provided for controlling drum 31.

The stick 17 is swung towards projected position by means of a pull line 40 anchored to the lower end of the stick, conveniently on pin 21. Conveniently this line 40 is in two passes, each passing over one of the two sheaves 19 journaled on pin 15 at each side of yoke 16. A desired pull is exerted upon the pull line 40 from a winding drum 41 which, like drum 31, will be provided with a common form of control mechanism (not shown).

In Fig. 1 this pull is exerted by means of a pull line 40' reeved around sheaves 42, 42 journaled at the upper end of a jack frame 43, and sheaves 44, 44 journaled upon a suitable mast or stationary support, such a mast or support being well known in the art.

In this form the inner ends of the two pull lines 40 are anchored upon the upper end of the jack frame, conveniently upon the pin 45, upon which the sheaves 42 are journaled.

In Fig. 3 the jack frame 43 is omitted and 100

the sheaves 42 are journaled in a sheave block 43' and in this form the two passes of the line 40 are anchored upon an equalizer sheave 46 journaled in the block 43'.

5 In the form shown in Fig. 1 the jack frame 43 is stepped at its lower end upon platform 13, conveniently upon pin 12 upon which the lower end of the boom is stepped.

The operation is as follows:

10 With the parts in the positions shown in the drawings, inward pull upon lines 40 will swing the boom upwardly, and inward pull on line 30 will draw the bucket towards the base of the boom, the free end of the boom 15 swinging upwardly and the bucket stick swinging on pin 15 and, by reason of the action of links 20 (Fig. 1) or links 20' (Fig. 3) sliding outwardly through yoke 16. The operator, by independently manipulating the 20 two winding drums 31 and 41, may swing the bucket stick from the position shown in full lines in Fig. 1 to the position shown in dotted lines in Fig. 1 angularly relative to the boom, and may raise and lower the boom about its 25 step to bring the bucket to any desired position within the possible arc of swing and to any desired vertical position within the range of vertical swing of the boom.

We claim as our invention:

30 1. An excavator comprising a vertically swinging boom, a bucket stick pivotally and longitudinally slidably associated with the boom, a bucket on the lower end of said stick, a link connected at one end with the bucket 35 stick and at the other end to the boom, a pull line connected to said bucket, a second pull line connected to the lower end of the stick, and a pull line guide carried by the boom and engaging the under side of the last-mentioned pull line at an intermediate point in its length, and draft means by which said pull lines may be independently manipulated.

15 2. An excavator comprising a vertically swinging boom, a dipper stick longitudinally movably mounted on said boom, a dipper rigid on said stick, means associated with said dipper stick and connected to said boom for pivotal movement relative to said boom, linkage means connecting said boom and stick to effect elongation of the cutting stroke of the dipper by compelling longitudinal movement of said stick as said stick is swung downwardly, and instrumentalities for 30 swinging the stick in a vertical plane.

35 3. An excavator comprising a vertically swinging boom, a crane body supporting the boom, a dipper stick, a dipper rigid on said stick, means for slidably and pivotally supporting the dipper stick relative to the upper end of the boom, linkage means directly connected with said boom and with said dipper stick for causing longitudinal downward movement of said stick as it is swung downwardly relative to said boom, a pull line con-

nected with the dipper stick for swinging the same upwardly, and a pull line connected with said bucket for swinging said stick and bucket downwardly.

4. An excavator comprising a vertically swinging boom, a bucket stick pivotally and slidably associated with the boom, a bucket on the lower end of said stick, a link connected at one end with the upper end of said stick and at the other end connected with the boom at a point spaced from the upper end of said boom, a pull line connected to said bucket, a pull line connected to said dipper stick, and draft means by which said pull lines may be independently manipulated.

5. An excavator comprising a vertically swinging boom, a bucket stick pivotally and slidably associated with the boom, a bucket on the lower end of said stick, a link connected at one end with the upper end of said stick and at the other end connected with the boom at a point spaced from the upper end of said boom, a pull line connected to said bucket, a pull line connected to said dipper stick, a pull line guide carried by said boom and engaging the under side of said last mentioned pull line at an intermediate point in its length, and draft means by which said pull lines may be independently manipulated.

6. An excavator comprising a vertically swinging boom, a bucket stick pivotally and slidably associated with the boom, a bucket on the lower end of said stick, a link connected at one end with said stick at a point between said bucket and the point of pivotal and slidable association between the stick and the boom, the other end of the link being attached to the boom at a point spaced from the upper end of the latter, a pull line connected to said bucket, a pull line connected to the lower end of said stick, and draft means by which said pull lines may be independently manipulated.

7. An excavator comprising a vertically swinging boom, a bucket stick pivotally and slidably associated with the boom, a bucket on the lower end of said stick, a link connected at one end with said stick at a point between said bucket and the point of pivotal and slidable association between the stick and the boom, the other end of the link being attached to the boom at a point spaced from the upper end of the latter, a pull line connected to said bucket, a pull line connected to the lower end of said stick, a pull line guide carried by said boom and engaging the under side of said last mentioned pull line at an intermediate point in its length, and draft means by which said pull lines may be independently manipulated.

8. An excavator comprising a vertically swinging boom, a bucket stick pivotally and slidably associated with the boom, a bucket on the lower end of said stick, a link connected at one end with said stick at a point be-

tween said bucket and the point of pivotal and slidable association between the stick and the boom, the other end of the link being attached to the boom at a point spaced inwardly on said boom from the point of pivotal and slidable association between said stick and said boom, a pull line connected to said bucket, a pull line connected to the lower end of said stick, and draft means by which said pull lines may be independently manipulated.

10 In witness whereof, we have hereunto set our hands at Indianapolis, Indiana, this 6 day of April, A. D. one thousand nine hundred and twenty-nine.
